(57) **CLAIM**

The ornamental design for a “bracket for feeder”, as shown and described.

DESCRIPTION

FIG. 1 is a front perspective view of the bracket for feeder, showing my new design with environmental structure illustrated in broken lines and forming no part of the claimed design;

FIG. 2 is a rear perspective view of the bracket for feeder;
FIG. 3 is a front view thereof;

FIG. 4 is a rear view thereof;

FIG. 5 is a rear elevational view thereof, this view being a mirror image of the opposing left side elevational view of the bracket for feeder;

FIG. 6 is a top plan view of the bracket for feeder; and,
FIG. 7 is a bottom plan view of the bracket for feeder illustrated in FIGS. 1–6.
